UNITED STATES PATENT OFFICE.

JOHN WILLIAM FEARN, OF BIRMINGHAM, ENGLAND, ASSIGNOR OF ONE-HALF TO
DOUGLAS VAUGHN JOHNSTONE, OF BIRMINGHAM, ENGLAND.

EJECTOR MECHANISM FOR SMALL ARMS OF THE DROP-DOWN-BARREL TYPE.

Application filed March 28, 1923. Serial No. 622,305.

To all whom it may concern:

Be it known that JOHN WILLIAM FEARN, a subject of the King of Great Britain, residing at 81 Weaman Street, Birmingham, 5 England, has invented certain new and useful Improvements in Ejector Mechanism for Small Arms of the Drop-Down-Barrel Type, of which the following is a specification.

10 This invention consists in a new or improved ejector-mechanism for small arms of the drop-down barrel type, which is principally applicable to single-barrel guns, and comprises an ejector-retaining sear which is 15 housed in the barrel lump, and is, during the closing of the arm, lifted into engagement with the ejector slide by an abutment located on the body below the centre of the body joint-pin, whereas during the opening 20 of the said arm, the sear is retracted from the slide by a loose sector that is disposed in front of the barrel lump so as to ride upon the joint-pin, and obtains its sear-retracting motion from another body-abutment located 25 above the joint-pin centre.

Figure 1 is a sectional view of a single gun fitted with the improved ejector and showing the parts thereof in the positions they assume when the gun is closed.

30 Figure 2 is a similar view, but shows the gun opened and the ejector parts in the positions they assume after the same have operated to eject a spent cartridge from the chamber of the barrel.

35 Figure 3 shows the main parts of the ejector mechanism separately; also an elevation of the barrel lump wherein the said parts are housed.

The same reference numerals indicate 40 corresponding parts in the said figures.

In the improved ejector mechanism as illustrated, the ejector-leg 12 is located in a hole 12^a bored longitudinally from the rear of the barrel-lump 14 and is influenced by 45 an ejector spring 16 disposed between the blind end of the said hole and a collar on the leg; one side of the said leg being formed with a clearance 17 of suitable length (determined by the working throw 50 of the ejector) to afford an engagement for a transverse stop-pin 18, whilst at a suitable distance from the inner end of the said leg, a shoulder 19 is machined to constitute the rear bent or engagement for the sear 10: the rear 55 underside of the said shoulder being prefer-

ably bevelled as shown for the purpose hereinafter explained.

The sear, which is located in a hole 10^a drilled diagonally upwards from the forward end of the lump 14 into the ejector leg housing 12^a, consists of a slideable pin whose upper end is suitably shaped for engaging the back of the ejector-bent 19 whilst near its other end, the said pin is formed with a shoulder 10^b to constitute an engagement for the sear-retracting piece 13, and with a clearance for the stop-pin 10^c.

The retractor piece 13 consists of a loose sector that is housed in a curved recess 13^b in the front of the barrel-lump and is adapted to ride around the rear side of the body joint pin 15^a on the gun being opened or closed; its upper end 13^a being opposed to an abutment 15^b located on the action body above and forward of the centre of the joint 75 pin 15^a, whilst its lower-end 13^c bears on the shoulder 10^b of the sear-pin.

The retractor is of such dimension that when the gun is closed, the upper end 13^a projects somewhat beyond the front face of 80 the barrel lump so that on the gun being opened, the angular movement made by the body relatively to the drop-down barrel will cause the body-abutment 15^b to impinge 85 against the projecting end of the retractor and displace the latter clockwise within its seating 13^b, this movement being transmitted to the sear-pin 10 for disengaging the latter from the bent shoulder 19 and allowing the ejector-slide to be projected by 90 its spring. On the other hand, during the closing of the gun, the ejector slide is pushed forward by its head moving down the breech-face of the body, and as soon as the slide has been thus displaced as to take 95 the bent-shoulder beyond the sear-pin housing, the forward end of the sear-pin comes into contact with an abutment 15^d located on the body below the joint-pin centre. The

continuance of the relative movement of the barrel and body in the closing direction then effects an upward displacement of the sear-pin within its housing, which simultaneously re-engages the said sear pin with the bent shoulder of the extractor leg and also 100 displaces the retractor 13 counter-clockwise in its seating, causing its upper end to again project beyond the front face of the barrel lump into the path of the body-abutment 15^b.

In order to delay the disengagement of the sear-pin from the ejector slide until the breech has been opened sufficiently to give the necessary ejection clearance, the bent 5 shoulder may be formed (as shown in the drawing) so that the said sear-pin has to be displaced through a considerable distance before its upper end finally clears the bent shoulder. Or, alternatively, the retractor- 10 piece and the body-abutment 15^b may be proportioned and disposed so that a certain clearance exists between them when the gun is closed, which results that, on opening, the body moves through an appreciable distance relatively to the barrel before contact 15 is made between the said abutment 15^b and the retractor, and the disengagement of the sear pin is correspondingly delayed.

Having described my invention what I 20 claim and desire to secure by Letters Patent is:—

1. In an ejector mechanism for small arms of the drop-down barrel type, the combination of a barrel lump, an ejector slide mounted within said lump, an ejector-retaining sear mounted within the said barrel lump, an abutment located on the body of the arm below the center of the body joint pin and adapted to engage the inner end of 25 the ejector-retaining sear for lifting the same into engagement with the ejector slide during the closing of the arm, a loose retractor piece disposed in the front of the barrel lump so as to freely ride around the joint pin, and an abutment located on the body of the arm above the center of the joint pin and engaging the upper end of the loose retractor piece for moving the ejector-retaining sear out of engagement with the 30 ejector slide during the opening of the arm.

2. In an ejector mechanism for small arms of the drop-down barrel type, the combination of a barrel lump; an ejector slide mounted within said lump; an ejector-re-

taining sear mounted within the said barrel lump and having a shoulder at its lower inner end; an abutment located on the body of the arm below the center of the body joint pin and adapted to engage the inner end of the ejector-retaining sear for lifting the same into engagement with the ejector slide during the closing of the arm; a loose retractor piece disposed in the front of the barrel lump so as to ride freely around the body joint pin, the lower end of said loose retractor piece being adapted to engage the shoulder on the said ejector-retaining sear; and an abutment located on the body of the arm above the center of the body joint pin and engaging the upper end of the loose retractor piece for moving the ejector-retaining sear out of engagement with the ejector slide during the opening of the arm.

3. In an ejector mechanism for small arms of the drop-down barrel type, the combination of a barrel lump; and ejector slide mounted within the said barrel lump; and ejector-retaining sear mounted within the said lump and normally engaging the ejector slide to maintain the same in non-ejecting position during the time that the arm is in closed position; a loose segmental retractor piece disposed in the front of the barrel lump and adapted to move around the body joint pin, the lower end of said retractor piece engaging the said ejector-retaining sear; and an abutment located on the body of the arm above the center of the joint pin and engaging the upper end of the said loose segmental retractor piece, for moving the same about the body joint pin to disengage the ejector-retaining sear from the ejector slide during the opening of the arm.

In testimony whereof I hereunto affix my 85 signature.

JOHN WILLIAM FEARN.
